UNITED STATES PATENT OFFICE.

JACOB T. LANDGRAF, OF MACOMB, ILLINOIS, ASSIGNOR TO AMERICAN STEEL PRODUCTS CO., OF MACOMB, ILLINOIS, A CORPORATION OF ILLINOIS.

BROODER STOVE.

Application filed June 13, 1925. Serial No. 36,799.

To all whom it may concern:

Be it known that I, JACOB T. LANDGRAF, citizen of the United States, residing at Macomb, Illinois, have invented certain new and useful Improvements in a Brooder Stove; and I do hereby declare the following to be a full, clear, and exact description of the invention, such as will enable others skilled in the art to which it appertains to make and use the same.

My invention relates to stoves of the general class of which coal burning heating stoves are typical, and more particularly to means for simultaneously controlling both the air supply of the stove and a check draft. Among the objects of my invention is that of providing a stove in which the rate of burning is controlled both by the air supply of the stove and a check draft. Among the objects of my invention is that of providing a stove in which the rate of burning is controlled partly by the flow of hot gases through a by-pass from the ash-pit to the flue or flue chamber and partly by regulating the air supply of the stove. For this purpose my invention provides simple means operating in unison for controlling the direct passage of gases from the ash-pit to the flue and for controlling the supply of air for the stove. It also provides a construction particularly suitable for use in connection with a controlling thermostat supported by the stove and operated by changes of temperature in the air at some distance from the stove. More particularly, my invention provides a stove constructed so that the air supply is taken through a part of a duct operatively connecting the ashpit of the stove with the flue, provides dampers for controlling both the air supply and the movement of gases from the ashpit through the duct to the flue, and provides damper-operating means so arranged that both the flow of hot gases through the duct and a flow of cold air through the upper portion of the duct can afford the needed check draft.

In one of its immediate commercial aspects, my invention is particularly suitable

for use as the heater of a brooder and adapted also for use with a stove having a check draft chamber between the heating chamber of the stove and the flue. I am therefore illustrating and describing my invention in embodiments particularly suitable for this purpose, from which further and more detailed objects will also appear.

In the drawings, Fig. 1 is a central, longitudinal and vertical section through a brooder stove embodying my invention, also showing a portion of an adjacent brooder hood.

Fig. 2 is a horizontal section of the same stove, taken along the line 2—2 of Fig. 1.

Fig. 3 is a section similar to a portion of Fig. 1, but showing another embodiment of my invention, namely one employing two separately pivoted dampers instead of the single damper member of Fig. 1.

Fig. 4 is a vertical section through another embodiment of my invention, namely one in which the air inlet opens directly into the ashpit and in which one damper is disposed at the lower end of the by-pass duct.

In the embodiments of Figs. 1 and 2, my brooder stove includes a base section having a top 2 which forms the bottom of the ash-pit of the stove. This top 2 supports a second section 3 forming the sides of the ash-pit, and the section 3 in turn supports a heater section 4, the usual rocking grates 5 being provided adjacent to the bottom of the heater section for supporting the fuel.

The top of the heater section is shown as constructed after the manner of U. S. Patent No. 1,519,819 of Dec. 16, 1924 to Hugh L. Gaddis, namely as supporting a flue collar 6 adapted to receive the lower end of a flue pipe 7, a baffle plate 8 disposed for restricting the passage of hot gases from the heater section to the check draft chamber 9 as thus formed between the baffle plate and other upper wall portions of the stove, and a removable fuel door 10.

Overhanging the rear end of the stove and extending downwardly behind the rear wall 11 of the stove is a channel-sectioned

casting 12 which cooperates with the said rear wall 11 in forming a duct extending from the rear of the ashpit to the check draft chamber 9. This duct is provided with an air inlet, shown in Fig. 1 as formed by tilting a rear wall portion 13 of the duct rearwardly so as to afford an air inlet opening 14 disposed behind the upper portion of the said duct. Thus arranged, the duct 10 is adapted for serving two separate purposes, namely that of permitting the air supply for the stove to pass downward from the inlet 14 into the ashpit and that of permitting heated gases to pass upwards 15 from the ashpit through the entire length of the duct to the check draft chamber 9 and from this to the flue pipe.

To control the operation of the duct for these two purposes, I provide two dampers 20 15 and 16, here shown as parts of a single damper member pivoted on a pin 17 which extends transversely of the stove through the channel-sectioned casting 12. The damper member also has rigidly connected to it an arm 28 which is connected by a link 18 to the lower or pivoted lever 19 of a thermostatic regulator. This regulator consists of a bracket 20 bolted to the back of the stove and carrying a downwardly 25 extending pin 21 on the lower head of which the pivot member 19 is pivoted at its rear end, the pivoted member 19 being pivoted at its forward end to the link 18. Interposed between the parts 19 and 20 are the 30 thermally expansible means, here shown as a pair of superposed hollow diaphragms or so called thermostatic wafers, which diaphragms contain the usual liquid vaporizable at a temperature below that to which 35 the air adjacent to the diaphragms is to be heated.

By adjusting the pivot bolt 21, the control mechanism is regulated so that when the air adjacent to the diaphragms 22 is cold, the 40 greater weight of the left hand side of the damper member (which consists of the two dampers 15 and 16) will rock this into position shown in full lines in Fig. 1, this damper member being suitably proportioned in weight for that purpose. When 45 in this position, the damper 15 effectively closes the portion of the duct between the air inlet and the check draft chamber 9, while the damper 16 is raised so as to provide a wide opening of the air inlet. Consequently, air can pass freely from this inlet through the lower portion of the duct into the ashpit to supply the air needed for the combustion of the fuel on the grate. 50

As soon as the stove has warmed sufficiently to raise the temperature of the surrounding air, the thermostatic wafers 22 expand, thereby pressing the lever 19 downwards and acting through the link 18 to 55 swing the damper member in a direction

which is clockwise in Fig. 1. In doing this, the damper member first reaches an intermediate position in which the damper 16 contracts the air inlet so as to throttle the amount of entering air, while the damper 15 partly opens the connection to the upper portion of the duct. When the damper member is in this medial position, the heating of air in the duct through the rear wall 11 tends to cause an upward movement of air through the duct to the check draft chamber, thereby serving to some extent as a by-pass for air from the heater to the check draft chamber. At the same time, some air may still enter the firebox through the lower rear portion of the said duct, and the two actions will combine to cause the fuel to burn at a reduced rate. 70 75 80 85

If this checking action is insufficient, the thermostatic control will swing the two dampers further, and when the inlet damper 16 is almost in its closure position, the flow of hot gases up the duct may carry the relatively small amount of cool entering air up with it to the flue, thereby cooling the latter and further checking the draft from the heater chamber to the flue through the flue chamber 9. Or, if the adjacent air is warmed still more, the continued expansion of the thermostatic wafers will move the damper member to the extreme checking position, namely that in which the damper 15 fully opens the connection between the two portions of the duct and in which the damper 16 entirely closes the air inlet. With the 90 95 100 damper member in this position, no air whatever is admitted to the ashpit or below the grates, but the heating of the air within the duct through the hot rear wall 11 of the heater chamber causes an upward movement of air or gases within this duct. Consequently, still more of the hot gases in the heater chamber will be drawn down through the bed of fuel into the firebox and up through the said duct to the check 105 110 115 draft chamber and the flue, and this downward drawing of the gases through the fuel will exert a powerful checking action on the rate of combustion of the fuel. 120

Owing to the combined action thus obtained by concurrently moving both of the dampers, I am able to secure a highly sensitive and effective control of the stove, thereby making my stove particularly desirable for uses where a fairly close regulation of the surrounding temperature is desired. Furthermore, by locating the controlled air inlet at a considerable height above the floor, I provide the air supply for the stove at a point well up under the hood. By doing this, I avoid the chilly draft to which the chicks would be subjected if the air supply was taken from a point near the bottom of the stove so as to cause inward currents of cold air close to the floor. 125 130

However, while I have heretofore described my invention in connection with a particular type of brooder stove and in an embodiment employing a single damper member, I do not wish to be limited to these or other details of the construction and arrangement thus disclosed, it being obvious that many modifications might be made without departing either from the spirit of my invention or from the appended claims.

For example, Fig. 3 shows two separate dampers 25 and 26 employed respectively for controlling the upper portion of the by-pass duct and for controlling the inlet, each of these dampers being separately pivoted and provided with a separate lever arm. It also shows the lever arms of the two dampers as connected by a link 27 which cooperates with the usual thermostatically actuated link 18 for effecting the required movement of the two dampers against the action of gravity.

Fig. 4 shows still another embodiment, namely one in which the air inlet is formed in the rear wall of the ashpit and in which the duct-controlling damper 30 is disposed for entirely shutting off the connection between the ash pit and the by-pass duct. In each case, this duct preferably has a wall in common with the heater chamber, so that the air or gases remaining in this duct when the duct-controlling damper is in its closure position will be heated and hence will be ready to cause an upward movement of gases through the duct as soon as this damper is even partly opened.

I claim as my invention:

1. In a stove, a heater chamber disposed above an ashpit and below a flue, a duct connecting the ashpit with the flue independent of the heater chamber and having an intermediate air inlet, two dampers respectively controlling the parts of the duct leading from the air inlet to the flue and to the ashpit, and connections for moving the dampers in unison so as to move one damper to its open position while moving the other damper to its closure position.

2. In a stove, a heater chamber disposed above an ashpit and below a flue, a duct connecting the ashpit with the flue and having an intermediate air inlet, and a single damper member having two parts respectively disposed for controlling the passage of air from the said inlet to the ashpit and for controlling the part of the duct between the air inlet and the flue, the said damper parts being disposed so that one thereof is in its closure position whenever the other thereof is in its open position.

3. In a stove, a heater chamber disposed above the ashpit and below a flue, a duct connecting the ashpit with the flue, an air inlet affording the normal air supply for the stove through the ashpit, a damper

controlling the portion of the duct above the air inlet, a second damper controlling the air inlet, and connections whereby one damper moves to its open position whenever the other damper moves to its closure position.

4. In a stove, a heater chamber disposed above an ashpit and below a flue, a duct connecting the ashpit with the flue and having one wall in common with the heater chamber, the duct having an air inlet intermediate its ends, a damper controlling the air inlet, a second damper controlling the part of the duct between the air inlet and the flue, and connections whereby one damper is moved to its open position whenever the other damper is moved to its closure position.

5. In a stove, a heater chamber disposed above an ashpit and below a flue, a duct connecting the ashpit with the flue and having an air inlet at a considerable height above the ashpit, and means responsive to the temperature at a point spaced from the heater whereby a rise in temperature decreases the admission of air through the inlet and increases the freedom with which hot gases can pass up the duct from the ashpit to the flue.

6. In a stove, a heater chamber disposed above an ashpit and below a flue, a duct connecting the ashpit with the flue outside of the heater chamber, the duct having an air inlet and the ashpit being laterally closed so that the air supply for the heater chamber is normally drawn entirely through the said air inlet and through the portion of the duct between the ashpit and the said air inlet, a damper controlling the air inlet, a second damper controlling the portion of the duct between the air inlet and the flue, and connections for conjointly moving the two dampers so that either thereof will be moved towards its closure position while the other is moving towards its open position.

7. In a stove, a heater chamber disposed above an ashpit and below a flue, a check draft chamber interposed between the heater chamber and the flue and connected to both thereof, a by-pass duct connecting the ashpit with the check draft chamber independently of the heater chamber, an air inlet normally affording the air supply for the stove through the ashpit, and conjointly actuated means for controlling the air inlet and the passage of gases through the duct from the ashpit to the check draft chamber.

8. A stove as per claim 7, in which the duct is disposed in heat conducting relation to the heater chamber.

9. In a stove, a heater chamber disposed above an ashpit, air admitting means connected to the ashpit, a flue connected to the upper portion of the heater chamber by

pass connection leading from the ashpit to the flue, and control means associated with the air admitting means and the by-pass connection; the control means being movable from one to another of two positions in which either the air admitting means or the by-pass connection is closed while the other thereof is open; the by-pass connec-

tion being disposed so as to be heated from the heater chamber and the control means being disposed when in intermediate position to cooperate with the by-pass connection in admitting air to the flue for checking the draft of the flue.

Signed at Macomb, Illinois, May 29, 1925.
JACOB T. LANDGRAF,
